UNITED STATES PATENT OFFICE.

JAMES W. KENNEDY, OF CHICAGO, ILLINOIS, ASSIGNOR, BY MESNE ASSIGNMENTS, TO THE KENNEDY TYPEWRITER COMPANY OF MANHATTAN, OF NEW YORK, N. Y., A CORPORATION OF NEW YORK.

TYPE-WRITING MACHINE.

No. 874,407.

Specification of Letters Patent.

Patented Dec. 24, 1907.

Application filed April 2, 1904. Serial No. 201,284.

To all whom it may concern:

Be it known that I, JAMES W. KENNEDY, a subject of the King of Great Britain, residing at Chicago, Cook county, Illinois, have 5 invented certain new and useful Improvements in Type-Writing Machines, of which the following is a complete specification.

This invention relates to typewriting machines, and relates particularly to means for 10 supporting and shifting the platen.

As the invention relates to means for supporting and shifting the platen, the object of the invention is to provide means for this purpose, which will be simple, strong and 15 durable, and which will operate to support the platen rigidly in all positions without play or lost motion.

The invention consists of the various features, combinations of features and details 20 of construction hereinafter described and claimed.

In the accompanying drawings illustrating 25 my invention,—Figure 1 is a partial top plan view of a typewriting machine embodying my invention. Fig. 2 is a front sectional elevation on the line 2—2 of Fig. 3. Fig. 3 is a sectional side view on the line 3—3 of Fig. 1. Fig. 4 is an enlarged sectional elevation on the line 4—4 of Fig. 1. Fig. 5 is a sectional elevation on the line 5—5 of Fig. 4. Fig. 6 is a side view of the parts shown in Fig. 5; and Figs. 7, 8, 9, 10, 11, 12 and 13 are enlarged detail views of various parts of the machine.

35 Referring now to the drawings, 1 designates the frame of the typewriter, and 2 the platen thereof.

The platen 2 is revolvably mounted in a suitable frame, designated as a whole by A, 40 consisting of end plates 3 rigidly connected by transverse rods 4, preferably disposed below and in the rear of the platen 2. The frame A is pivotally connected by links 5 to a carriage 6 mounted, so as to be freely movable transversely of the machine, on guide rods 7 and 8 secured, respectively, in upright standards 9 and 10, on the machine frame. As shown, the carriage 6 is provided with two bearings located a considerable 45 distance apart and which engage the rod 7 symmetrically on both sides of the center of the platen 2, the distance between the standards 9 being such as to provide for desired

movement of the platen transversely of the machine. As shown, also, the bearing for 55 the rod 8 is formed in a central rearward arm 11 on the carriage 6 and the movement of said carriage transversely of the machine is adapted to be regulated by adjustable stops. In the preferable construction shown, 60 see Figs. 9 and 10, said stops consist of what may be termed sleeves 12 splined to the rod 8, one on each side of the arm 11, each of which comprises a rectangular enlargement 13. Formed in the lower side of the rod 8 65 are notches 14, which are adapted to be engaged by spring catches carried by the sleeves 12. As shown, said catches consist of wires, comprising parallel end sections 15, which are fitted to suitable holes in the rectangular enlargements of the sleeves 12, and intermediate transverse sections 16, which connect the end sections 15 at their lower ends. The intermediate sections 16 of said wires are fitted to suitable slots or grooves 70 in the lower sides of the rectangular enlargements 13 of the sleeves 12 and are adapted to engage the notches 14 on the rod 8. The end sections 15 of said catches project above the rectangular enlargement 13 of said sleeves 80 12, and are rigidly secured to plates 18. Inserted beneath the plates 18, being preferably confined in suitable recesses in the sleeves 12, are springs 19, which operate to maintain the intermediate sections 16 of 85 said catches normally in engagement with the notches 14 in the rod 8 and provide for disengaging said catches from said notches, when it is desired to adjust said stops.

In the preferable construction shown, the 90 links 5 comprise a plurality of parallel links of equal lengths arranged in pairs symmetrically on both sides of the center of the platen 2, one above the other. As shown, the links 5 are connected at one end to the 95 rear upper and lower rods 4 of the platen frame A and at their other ends to rods 20 secured in suitable arms on the carriage 6. With the described arrangement of the links 5 it is obvious that pivotal movement of the 100 platen frame A will operate to raise and lower the platen and other parts carried thereon bodily, in parallel position, while at the same time affording a very strong and rigid connection of said platen frame to the 105 carriage 6. The platen 2 is supported in de-

sired vertical position and is adapted to be raised and lowered to provide for shifting from one set of characters on the type-bars to another, in the following manner:

- 5 Secured to the lower rods 4 of the platen frame A is a bracket 21, revolvably mounted in the lower end of which is a wheel or roller 22 which rests upon a bar 23, which extends transversely across the machine beneath the 10 platen frame A parallel with the rods 7 and 8, the ends of which are fitted to suitable upright guides formed in brackets 24, which depend from the under side of the top of the machine frame 1. As shown, see particularly Fig. 11, the guides for the bar 23 consist of slots 25 formed in said brackets 24 and the movement of said bar in said slots is adapted to be limited and adjusted by stop screws 26 threaded through the top of the 15 machine frame and the ends of the brackets 24 into the path of travel of said bar. Secured in suitable holes in the ends of the screws 26 are plugs 27 of leather or other soft material, which project slightly beyond the ends of said screws and form cushions, which operate to lessen the jar and noise due to contact of said bar with said screws in shifting the platen. The screws 26 are 20 adapted to be secured in any desired adjustment by means of binding nuts 28, in a familiar manner. The bar 23 is adapted to be raised and lowered, to shift the platen 2, by means of levers 29 rigidly secured to a rod 30 revolvably mounted in the frame of the 25 machine, preferably adjacent to the bottom thereof. The rear ends of the levers 29 are connected with the ends of the bar 23 by links 31 and their front ends are connected to shift levers 32 by means of links 33.
- 30 For convenience, a shift lever 32 is provided at each side of the machine and to provide for shifting the platen by means of either of said levers independently of the other, the links 33 are connected to the levers 29 by means of slots 34 in said links which engage suitable pins 35 in the levers 29, said slots being slightly longer than the travel of the pins 35 in the levers 29 and the pins 35 normally resting in contact with the upper 35 ends of said slots. With this construction, it is obvious that depressing either of the levers 32 will impart pivotal movement to both levers 29, thus raising both ends of the bar 23 the same distance and maintaining the same parallel with the rods 7 and 8, without imparting movement to the other shift lever 32, as the pin 35 in the lever 29 connected thereto will merely move downwardly in its slot 34.
- 40 To insure a uniform impression of the type, it is essential that the platen 2 shall always be in the same position relative to the angular travel of the type bars. To effect this end, where the platen moves on the arc of a 45 circle in being shifted, as in a machine em-

bodying my invention, the axes of the points of pivotal attachment of the links 5 to the carriage 6 should all be in the same plane, parallel to a plane normal to the surface of the platen at the point where the type strike 70 the same and the position of the stops which define the normal and shifted positions of the platen should be such that the angular movement of the platen will be the same on both sides of a line normal to the plane in which 75 the points of pivotal attachment of the links 5 to the carriage 6 are located, in the present instance, on both sides of a horizontal line.

Any desired or approved form of carriage feed and letter spacing mechanism may be 80 used, as, however, they form no part of the present invention and can be readily supplied by any mechanic familiar with typewriter construction, means for this purpose are not herein shown or described in detail. 85

I will next describe the construction of the line spacing mechanism, particular reference being had to Figs. 4, 5, 6, 7 and 8, but I do not claim these devices in this application, they being the subject matter of the divisional application numbered 210,464, filed 90 May 31, 1904.

Secured to the shaft of the platen 2 is a ratchet wheel 36, the teeth of which are adapted to be engaged by a spring pawl 37 95 pivoted on an arm 38 pivoted to the shaft of the platen 2 at the side of the ratchet wheel 36. Pivotal movement is adapted to be imparted to the arm 38 to advance and retract the pawl 37, in the following manner:— 100 Revolvably mounted in suitable bearings in lugs 39 on an end plate 3 of the platen frame A is a rod or lever 40, secured in which is a lateral arm 41, the free end of which is connected to the arm 38 by means of a link 42. 105 In the preferable construction shown, see Fig. 7, the end of the arm 41 on the rod or lever 40 is fitted to a suitable bearing in a block 43 pivotally mounted between lugs 44 formed at the end of the link 42, thus providing for angular movement of the arm 41 when the arm or lever 40 is rotated to operate the line spacing mechanism. A suitable hole or opening 45 is formed in the plate 3 through which the arm 41 extends, said 110 opening 45 being made of such length as to provide for desired movement of said arm 41.

Cooperating with the actuating pawl 37, is a retaining pawl adapted to engage the teeth of the ratchet wheel 36 to prevent the 115 platen 2 from being moved rearwardly when the actuating pawl 37 is retracted. As shown, said retaining pawl consists of a spring arm 46, which projects laterally from the plate 3 over said ratchet wheel, revolvably 120 mounted in the end of which is a wheel or roller 47, which engages the teeth of said ratchet wheel. Any other desired or approved form of retaining pawl may, however, be used. 130

The feed of the line spacing mechanism and thus the distance between successive lines is controlled and regulated by means of a suitable adjustable stop, which limits the 5 angular movement of the arm 41 on the lever 40. As shown, said stop consists of a plate 48 secured to a stub shaft 49 revolvably mounted in the plate 3 of the platen frame A. Formed on said plate 48 are a succession 10 of steps or notches 50, 51 and 52, located at different distances from the axis of the stub shaft 49 and so disposed that by turning said plate 48 into proper positions any one of said surfaces may be brought into the path of 15 travel of the arm 41, the relation being such that the step or notch 50 will permit a maximum movement of the arm 41, say the equivalent of a feed of three teeth of the ratchet wheel 36, the step or notch 52 a minimum 20 movement of said lever arm, say the equivalent of one ratchet tooth, and the step 51 a movement of said lever arm intermediate the steps 50 and 52, say two ratchet teeth. The plate 48 is adapted to be turned 25 into different positions to secure the different feeds by means of an arm 53 secured to the stub shaft 49 outside of the plate 3 and to be secured in desired position by means of a pin 54 thereon adapted to engage holes 55 in said 30 plate. To provide for engagement and disengagement of the pin 54 with the holes 55, the arm 53 is preferably a spring arm.

In addition to operating the line spacing mechanism the rod or lever 40 is also used to 35 retract the platen carriage. In the preferable construction shown, the forward end of said rod or lever 40 is bent downwardly below the bearings of said rod in the lugs 39 into close proximity to the keyboard of the 40 machine in convenient position for manipulation by the operator. With this construction, it is obvious that a pull on the rod 40 below the line of its bearing in a direction to retract said carriage will at the same time 45 operate the line spacing mechanism.

The rod or lever 40 is maintained normally at one limit of its pivotal movement by means of a suitable spring applied thereto. As shown, see Fig. 8, this is effected by 50 means of a spring 56 one end of which is secured to a collar 57 and the other end to the rear lug 39 in which the rod 40 is supported. To provide for adjusting the tension on said 55 spring 56, the collar 57 is loose on said rod or lever and is adapted to be secured thereto in any desired angular adjustment by means of a set screw. As shown, also said spring is inclosed in a recess formed in the collar 57.

Contact of the arm 41 with the upper end 60 of the slot 45 operates to limit the movement of the rod or lever 40 under the influence of the spring 56.

The platen 2 is adapted to be turned manually to provide for inserting and adjusting 65 the paper in the machine by means of knobs

or finger grips 58 on the platen shaft, in a familiar manner. In order that the actuating pawl 37 may not interfere with the rearward movement of the platen by means of the knobs or finger grips 58, means are provided to disengage said pawl from the teeth of the ratchet wheel when said pawl is in retracted position. As shown, the means for this purpose consist of a pin 59 secured in the plate 3 of the platen frame A, which projects laterally into the path of travel of a cam surface formed on a rearward extension 60 of the actuating pawl 37, the relation being such that when said pawl is fully retracted the cam surface on said rearward extension 60 will engage the pin 59 in such manner as to move said pawl 37 pivotally to disengage the same from the ratchet teeth in the desired manner.

The shift levers 32 and the type-bar operating levers, not shown, are pivotally supported in operative position in the following manner:—Formed on the machine frame in suitable position is a transverse bar 61, the lower edge of which forms a blunt knife edge 85 adapted to engage notches 62 formed in the upper edges of said shift levers 32 and the type-bar levers adjacent to their rear ends. Said shift levers and type-bar levers are maintained in proper lateral positions by 90 combs 63 and 64 secured in fixed positions on the machine frame, the teeth of which embrace the sides of said levers and guide the same in their pivotal movement. Said shift and typebar levers are maintained normally 95 in raised positions by springs 65, which connect said levers with a rigid support on the machine frame, as shown, a rod 66. In order to secure a uniform action of said shift and type-bar levers, means are provided for 100 adjusting the tension of said springs 65. To effect this end, said springs, instead of being secured directly to the rod 66, are attached to separate blocks 67 secured to said rod so as to be adjustable towards and from the 105 shift and type-bar levers. In the preferable construction shown, see Figs. 12 and 13, a groove or slot 68 is formed in the under side of the rod 66 to which the edges of the blocks 67 are fitted, the lengths of said blocks being 110 preferably equal to the distance from center to center of adjacent levers. With this construction, it is obvious that said blocks will fill the slot 68 from end to end and that the adjacent surfaces of adjacent blocks will operate in connection with the sides of the slot 68 to prevent said blocks from turning in said slot. The blocks 67 are secured to the rod 66 by means of headed screws 69, the body portions of which pass freely through 115 suitable holes in the top of the rod 66 and are threaded into said blocks. With this construction, it is obvious that by turning the screws 69 one way or the other, the blocks 67 120 are adjusted towards and from the oper-

125

130

ating levers, thereby correspondingly lessening or increasing the tension on the springs 65, in the desired manner.

I claim as my invention:—

- 5 1. In a typewriting machine, the combination of a platen frame comprising end plates and transverse rods rigidly connecting the same at their rear upper and lower edges, a carriage, guides on which said carriage is 10 movable transversely of the machine and upper and lower links pivotally connected to rear upper and lower platen frame rods at one end and to said carriage at the other, substantially as described.
- 15 2. In a typewriting machine, the combination of a platen frame, comprising end plates and transverse rods rigidly connecting said end plates, a carriage, guide rods on which said carriage is movable transversely 20 of the machine, a central arm on said carriage in which the bearing for one of said guide rods is formed, adjustable stops on said guide rod, upper and lower links pivotally connected to platen frame rods at one 25 end and to said carriage at the other, a bar on which said platen frame is supported and means to raise and lower said bar, substantially as described.
3. In a typewriting machine, the combination of a platen frame, a carriage to which 30 said platen frame is pivoted, guides on which said carriage is movable transversely of the machine, a bar on which said platen frame is supported, guide slots to which the ends of 35 said bar are fitted, stops which limit the movement of said bar in said guide slots and means to raise and lower said bar, substantially as described.
4. In a typewriting machine, the combination of a platen frame, a carriage to which 40

said platen frame is pivoted, guides on which said carriage is movable transversely of the machine, a bar on which said platen frame is supported, guide slots to which the ends of 45 said bar are fitted, the ends of said slots being closed and forming stops which limit the movement of said bar, a transverse rod, levers secured thereto at both sides of the machine, links which connect said levers with said bar, a shift lever, a lever arm on said 50 transverse rod and a link which connects said lever arm with said shift key, substantially as described.

5. In a typewriting machine, the combination of a platen frame, a carriage to which 55 said platen frame is pivoted, guides on which said carriage is movable transversely of the machine, a bar on which said platen frame is supported, guide slots to which the ends of 60 said bar are fitted, the ends of said slots being closed and forming stops which limit the movement of said bar, a transverse rod, levers secured thereto at both sides of the machine, links which connect said levers with said bar, shift levers at both sides of the 65 machine, lever arms on said transverse rod and links which connect said lever arms with said shift keys, the connection between said 70 lever arms and links comprising slots in one thereof and pins secured in the other which engage said slots, substantially as described.

In testimony, that I claim the foregoing as my invention, I affix my signature in presence of two subscribing witnesses, this 29th day of March, A. D. 1904.

JAMES W. KENNEDY.
